The ornamental design for a sleeve with surface indicia, as shown and described.

DESCRIPTION

FIG. 1 is a top perspective view of a first embodiment of the sleeve with surface indicia in accordance with one aspect of my new design;

FIG. 2 is a top perspective view of a second embodiment of the sleeve with surface indicia in accordance with another aspect of my new design;

FIG. 3 is a top perspective view of a third embodiment of the sleeve with surface indicia in accordance with another aspect of my new design;

FIG. 4 is a top perspective view of a fourth embodiment of the sleeve with surface indicia in accordance with another aspect of my new design;

FIG. 5 is a top perspective view of a fifth embodiment of the sleeve with surface indicia in accordance with another aspect of my new design;

FIG. 6 is a top perspective view of a sixth embodiment of the sleeve with surface indicia in accordance with another aspect of my new design;

FIG. 7 is a top perspective view of a seventh embodiment of the sleeve with surface indicia in accordance with another aspect of my new design;

FIG. 8 is a top perspective view of an eighth embodiment of the sleeve with surface indicia in accordance with another aspect of my new design;

FIG. 9 is a top perspective view of a ninth embodiment of the sleeve with surface indicia in accordance with another aspect of my new design;

FIG. 10 is a top perspective view of a tenth embodiment of the sleeve with surface indicia in accordance with another aspect of my new design;

FIG. 11 is a top perspective view of an eleventh embodiment of the sleeve with surface indicia in accordance with another aspect of my new design;

FIG. 12 is a top perspective view of a twelfth embodiment of the sleeve with surface indicia in accordance with another aspect of my new design;

FIG. 13 is a top perspective view of a thirteenth embodiment of the sleeve with surface indicia in accordance with another aspect of my new design;

FIG. 14 is a top perspective view of a fourteenth embodiment of the sleeve with surface indicia in accordance with another aspect of my new design;

FIG. 15 is a top perspective view of a fifteenth embodiment of the sleeve with surface indicia in accordance with another aspect of my new design;

FIG. 16 is a top perspective view of a sixteenth embodiment of the sleeve with surface indicia in accordance with another aspect of my new design;

FIG. 17 is a top perspective view of a seventeenth embodiment of the sleeve with surface indicia in accordance with another aspect of my new design;

FIG. 18 is a top perspective view of an eighteenth embodiment of the sleeve with surface indicia in accordance with another aspect of my new design;

FIG. 19 is a top perspective view of a nineteenth embodiment of the sleeve with surface indicia in accordance with another aspect of my new design;

FIG. 20 is a top perspective view of a twentieth embodiment of the sleeve with surface indicia in accordance with another aspect of my new design;

FIG. 21 is a top perspective view of a twenty-first embodiment of the sleeve with surface indicia in accordance with another aspect of my new design;

FIG. 22 is a top perspective view of a twenty-second embodiment of the sleeve with surface indicia in accordance with another aspect of my new design;

FIG. 23 is a top perspective view of a twenty-third embodiment of the sleeve with surface indicia in accordance with another aspect of my new design;

FIG. 24 is a top perspective view of a twenty-fourth embodiment of the sleeve with surface indicia in accordance with another aspect of my new design;

FIG. 25 is a top perspective view of a twenty-fifth embodiment of the sleeve with surface indicia in accordance with another aspect of my new design; and,

FIG. 26 is a top perspective view of a twenty-sixth embodiment of the sleeve with surface indicia in accordance with another aspect of my new design.

In the drawings, the broken lines depict unclaimed subject matter only and form no part of the claimed design.
